UNITED STATES PATENT OFFICE.

DANIEL P. JEFFERIES AND JAMES G. RODGERS, OF SPRINGFIELD, OHIO,
ASSIGNORS TO THE TRICYCLE MANUFACTURING COMPANY, OF SAME
PLACE.

DESIGN FOR A BABY-CARRIAGE BODY.

SPECIFICATION forming part of Design No. 19,231, dated July 23, 1889.

Application filed December 3, 1888. Serial No. 292,534. Term of patent 14 years.

To all whom it may concern:

Be it known that we, DANIEL P. JEFFERIES and JAMES G. RODGERS, citizens of the United States, residing at Springfield, in the county 5 of Clark and State of Ohio, have invented and produced a new and original Design for Baby-Carriage Bodies, of which the following is a specification, reference being had to the accompanying drawings, forming a part 10 thereof.

Figure 1 illustrates a side elevation of a baby-carriage body showing our design; Fig. 2, a front view of the same, and Fig. 3 a rear view thereof.

15 The leading feature of our design consists of panels having a surface ornamentation composed of figures raised or in relief, and of open-work; and such feature also consists of the panel or panels having surface ornamentation so composed of figures raised or in 20 relief.

The letter A designates a side of a baby-carriage body, and the letters B and C the front and rear thereof, respectively. The 25 sides are composed of open-work D, as illustrated, in which E designates the serpentine rail, curved into substantially semicircular form at the ends and embellished at the upper, forward, and rear extremities with curved 30 branches F, terminating in the scrolls G and H, with the intermediate connecting-bars I

and rings J. At intermediate points of the side are posts K and rounds L. Within the loop portion of the rail is a second rail M, and in the intermediate space are ribs N, and in 35 the area within the rail M is the fanciful scroll-work O. The surface ornamentation is composed of a panel P, ornamented with figures in relief. These figures are typical of flowers or flowers and geometrical figures. 40 In Fig. 1 the panel P is also shown with raised ribs Q, to add to the effect of the ornamentation. Between the panel and the surrounding portion of the rail E appear the scroll-ribs R. Figs. 1 and 2 respectively show the 45 front and rear of the body.

Having thus fully described our invention, what we claim as new, and desire to secure by Letters Patent, is—

1. The design of a baby-carriage body, substantially as herein described and shown. 50
2. In a design for a baby-carriage body, a panel, substantially as herein shown and described.

In testimony whereof we affix our signatures 55 in the presence of two witnesses.

DANIEL P. JEFFERIES.
JAMES G. RODGERS.
